UNITED STATES PATENT OFFICE.

PETER L. WEIMER, OF LEBANON, PENNSYLVANIA.

IMPROVED MACHINE FOR COILING METAL PIPE.

Specification forming part of Letters Patent No. 25,294, dated August 30, 1859.

To all whom it may concern:

Be it known that J. PETER L. WEIMER, of Lebanon, Lebanon county, in the State of Pennsylvania, have invented a new and useful Machine for Coiling Metal Pipe; and I do hereby declare that the following is a full, clear, and exact description of the construction and operation of the same, reference being had to the annexed drawings, making part of this specification, in which—

Figure 1 is a longitudinal elevation. Fig. 2 is an end view. Fig. 3 is a detached end view of the coiling-cylinder, enlarged to show more plainly its construction. Fig. 4 is a view of one of the guide-wheels and part of the coiling-cylinder, also enlarged so as to more fully show its construction, the letters of reference on all the different figures corresponding.

The nature of my invention consists in a suitable spiral-grooved cylinder and two guide-wheels, so arranged that a piece of metal pipe can be coiled on the grooved cylinder without much altering its cross section by bending; also, in the peculiar arrangement of the coiling-cylinder, whereby the cylinder and finished coil may be removed from the shaft of the machine and the cylinder be removed from the coil without injury to the coil or cylinder.

The construction and operation of my machine are as follows:

On a suitable bed, A, are placed two stands, B, in which revolves the shaft C by means of the hand-levers D or suitable gearing. One end of the shaft C projects beyond the bearing-stand B, and carries the grooved coiling-cylinder E.

F is a movable plate under the coiling-cylinder E. One end of this plate is supported on a screw-jack, G; the other end is hinged into a frame, H, which frame slides vertically in the stand B, and is raised and lowered by means of another jack-screw, G. Near each end of the plate F is fastened the small stands I I. Through the eye of these stands passes the shaft J J. On this shaft, near each end and inside of I I, are placed the triangular pieces K K, which pieces are free to vibrate on the shaft J J through the two upper holes of K K, and, connecting them, pass the guide-wheel shafts L L. On these shafts are placed the guide-wheels M M. These wheels have turned into their face a semicircular groove, which

groove, in connection with the semicircular groove in the bottom of the square groove on the coiling-cylinder, forms a true circle of the diameter of the pipe to be coiled.

The coiling-cylinder E is composed of a number of staves, with the joints radiating from the center, except the joints of the stave N, which radiate in an opposite direction, thus forming a key-stave, the largest part of which is toward the center of the cylinder. This key-stave keeps and tightens the other staves in their position in the hoops O O. The cylinder has now the appearance of a common straight-sided barrel, with close-fitting joints of the staves. On the circumference of the cylinder is worked spirally a square groove (say, for a cylinder to bend two-inch-diameter pipe) one-half inch deep and two and one-half inches wide. In the bottom of this square groove is now worked the semicircular groove two inches diameter. This leaves an offset in the square groove of one-fourth inch on each side of the semicircle groove. The guide-wheels M M (for same sized groove) measure two and one-half inches on the face and have the semicircular groove of two inches diameter turned onto their face. These wheels, it will be observed, run in the square groove of the cylinder E, which groove causes the guide-wheels to follow the groove in cylinder E, and at all places and positions the groove in the cylinder, in connection with the groove in the guide-wheel, forms a perfect circle of the diameter of the pipe to be coiled. The object in radiating the joints of the stave N in an opposite direction from the other staves is that when the pipe is coiled hot on the cylinder in cooling it contracts and draws the cylinder very tightly together; also, as measures must be provided for removing the coil from the cylinder, this stave is so-arranged that by loosening the screws that hold it to the ring the cylinder will fall to pieces and is removed from the coil.

P are set-screws to hold the cylinder on the shaft C, and also to so adjust it on the shaft that its surface will run true with the shaft.

It will be observed by referring to Fig. 2 that one of the guide-wheels is placed immediately under the center of the cylinder E and in contact with it. The second guide-wheel is placed beyond the first, also in contact with

E, these guide-wheels running, as above stated, in the square part of the groove on E. The object of the two guide-wheels will be better understood when the fact is made known that in coiling pipe on a cylinder the flattening does not take place at the point where the pipe first comes in contact with the cylinder, but after it has passed this point and between this point and a point marked X on Fig. 2. For this reason I introduce the second wheel to counteract this flattening and preserve the cross-section of the pipe.

The use of the two guide-wheels, more fully explained, is this: The wheel immediately under the cylinder guides the pipe in the groove of the cylinder and prevents it making short kinks; while the second wheel rounds up the pipe and causes it to preserve its cross-section. This effect I now fully produce by having the guide-wheels guided in the groove of the cylinder E, thus throwing all duty off of the pipe to guide the wheels to the groove on the cylinder, and leaving said wheels to act in connection with the cylinder as a pair of rolls act in rolling round iron. The eye or holes of the guide-wheels are made bell-mouthed, as shown at Fig. 4. This allows them (the wheels) to follow the groove on the cylinder, though the shafts on which they run may not be in perfect line.

The manner of operating my machine is as follows: The pipe being heated in a suitable furnace, such as is used by pipe-welders, is brought to the machine. The screw-jack G, carrying the hinged end of the plate F, is sufficiently lowered to allow the pipe to pass between the guide-wheels and cylinder. The pipe being inserted, the screw-jack is raised until the guide-wheels come in contact with the offset in the groove on the cylinder, when the pipe is fastened by a key to the lug S, cast on the cylinder. The cylinder, being now put in motion, coils the pipe in the groove, the guide-wheels operating as herein described. When the coil is completed, the jack-screws are lowered so as to clear the pipe, the set-screws P are loosened, and the coil and cylinder removed from the shaft. The screws holding the key-stave N are removed, and the

cylinder falls to pieces, and is removed from the coil. The staves being again set up in the hoops and fastened on the shaft, the machine is ready for making another coil.

The arrangement of the jack-screws, plate F, and guide-wheels allows any size coiling-cylinder to be used on the machine that may be desired.

I am aware that a pipe-coiling machine has been patented in which a former with open radial joints is used, which, by being driven back on a wedge-shaped shaft, causes the former to collapse sufficient to remove the pipe. Mention is also made that when the former is made in cone form it may not be necessary to make the former in section. I make no claim to either the open radial-joint former or the solid conical one, as neither will answer the purpose of my invention, the open radial joints allowing places at the joints in which the pipe has no support and will flatten the solid one, it being impossible to get the coil off of the former. I also make no claim to the single guide-wheel used, as described, at the bend of the pipe, as my machine rounds up the pipe after it has left this point, and practice shows that pipe in bending flattens most after leaving the bending-point, and to make a perfect coil must be rounded up after leaving this point.

Having thus fully described the nature of my invention, what I claim as my invention, and desire to secure by Letters Patent of the United States, is—

1. The coiling-cylinder E, with the peculiar-shaped groove, constructed and arranged as herein fully described and specified.
2. The arrangement of the two guide-wheels M, triangular piece K, and shafts L, when used in combination with the coiling-cylinder, and for the purpose as herein fully described and specified.
3. The movable plate F and jack screws G, for the purpose of adjusting the guide-wheel shafts L to any angle required.

PETER L. WEIMER.
